(57) **CLAIM**

The ornamental design for an endoscope sheath assembly, as shown and described.

DESCRIPTION

FIG. 1 is a front elevational view of the endoscope sheath assembly;

FIG. 2 is a side elevational view thereof;

FIG. 3 is an enlarged top plan view thereof;

FIG. 4 is a bottom plan view thereof;

FIG. 5 is a perspective view thereof;

FIG. 6 is an enlarged perspective view of the proximal end of the endoscope sheath assembly;

FIG. 7 is a perspective view of the inner portion of the endoscope sheath assembly with the cover removed for ease of illustration;

FIG. 8 is a front elevational view of the proximal end thereof;

FIG. 9 is a side elevational view of the proximal end thereof;

FIG. 10 is a top plan view of the proximal end thereof;

FIG. 11 is an enlarged bottom plan view of the proximal end thereof;

FIG. 12 is another perspective view of the proximal end of the endoscope sheath assembly;

FIG. 13 is an enlarged front plan view of the proximal connector for the endoscope sheath assembly;

FIG. 14 is a side elevational view of the proximal connector thereof;

FIG. 15 is an enlarged top plan view of the proximal connector thereof;

FIG. 16 is an enlarged bottom plan view of the proximal connector thereof; and,

FIG. 17 is an enlarged perspective view of the proximal connector thereof.

The broken line showing portion of an endoscope sheath assembly is included for illustrating environmental structure and forms no part of the claimed design.
